UNITED STATES PATENT OFFICE

172,209

COOKING RANGE

William H. Armstrong, Detroit, Mich., assignor
to The Tappan Stove Company, Mansfield,
Ohio, a corporation of Ohio

Application October 24, 1952, Serial No. 21,977

Term of patent 14 years

(Cl. D81—4)

To all whom it may concern:

Be it known that I, William H. Armstrong, a citizen of the United States of America and a resident of Detroit, in the county of Wayne and State of Michigan, have invented a new, original, and ornamental Design for a Cooking Range, of which the following is a specification, reference being had to the accompanying drawings, forming a part thereof, in which the figure shows a perspective view of a cooking range embodying my new design.

The left hand side of the cooking range, not shown in the drawing, is substantially the same as the right hand side thereof.

I claim:

The ornamental design for a cooking range, substantially as shown and described.
